Patented Apr. 6, 1920.

FIG. 4.

Inventor
Joseph A. S. Simone

334 J. W. Bryant,
Attorney.

UNITED STATES PATENT OFFICE.

JOSEPH A. S. SIMONE, OF INWOOD, NEW YORK.

ADJUSTABLE WINDOW-SCREEN.

1,336,101.

Specification of Letters Patent.

Patented Apr. 6, 1920.

Application filed May 21, 1919. Serial No. 298,723.

To all whom it may concern:

Be it known that I, JOSEPH A. S. SIMONE, a citizen of the United States of America, residing at Inwood, in the county of Nassau 5 and State of New York, have invented certain new and useful Improvements in Adjustable Window-Screens, of which the following is a specification.

The primary object of the invention is the provision of a screen for windows and similar openings, readily positioned and removed, when desired, and automatically retained when in use, the structure possessing great strength, and being easy and inexpensive to manufacture.

A further object of the invention is to provide an extensible window screen in a unitary structure serviceable in openings of varying widths and automatically retained 20 in operative position when in use.

A still further object of the invention is to provide a window screen readily fitted extensibly into a window having no portions liable to become disassembled, the device being manually contractible and automatically extensible for self-maintenance in the window until the removal thereof is desired.

With these general objects in view the invention consists of the novel form, combination, and arrangement of parts herein-after more fully described, illustrated in the accompanying drawings and then claimed.

In the drawings forming a part of this application and in which like reference characters designate corresponding parts throughout the several views,

Figure 1 is a plan view of the invention partially broken away, and with parts indicated by dotted lines,

Fig. 2 is a side elevation thereof.

Fig. 3 is a longitudinal sectional view taken upon lines III—III of Fig. 1, and

Fig. 4 is a view partly in end elevation 45 and partly in section, upon line IV—IV of Fig. 1.

Referring more in detail to the drawing, my invention comprises a rectangular frame composed of substantially U-shaped sections 50 10 and 11 with the sides 12 and 13 thereof, respectively, in telescoping relations. The said sides 12 and 13 as well as the ends or cross pieces 14 and 15, of the sections 10 and 11, respectively, are preferably formed 55 of sheet metal covered wood, as illustrated

in Figs. 3 and 4 of the drawing. The wooden portion 16 of the frame section 10 has the metal covering 17 while the wooden portion 18 of the section 15 is covered by metal 19.

A wire screen 20 of metal or other suitable foraminous material is mounted in the frame with one end thereof anchored at 21 in the end 14 of the section 10, while the sides of the screen 20 freely rest within longitudinal grooves 22 in the inner faces of the sides 12 of the frame 10 and extend through corresponding slots 23 in the inner faces of the tubular sides 13 of the section 11. A roller 24 is journaled longitudinally 70 within the end 15 of the section 11 with the screen 20 passing over same roller with its adjacent end secured to a slide plate 25. The plate 25 has T-shaped ends 26 slidable within grooves 27 in the inner faces of the 75 sides 13 parallel with the slots 23, while an outwardly turned or bent flange 28 upon the plate 25 is readily grasped for moving the plate toward the section 10 and drawing the frame sections together, reducing the 80 size of the invention.

Helical springs 29 are connected between the opposite ends of the cross members 14 and 15 being positioned in bores 30 and 31 of the sides 12 and 13 respectively. A guide 85 rod 32 is provided in each bore 31 within the springs 29 with their corresponding ends secured or doweled as at 33 in the opposite ends of the cross piece 15. The complete operation of the invention will be fully understood from this detailed description thereof, the springs 29 tending to force the sections 10 and 11 apart with the screen 20 exposed to its fullest extent and the flange 28 at the limit of its movement toward the 95 end 15 of the frame.

When desiring to place the invention into a window, the ends 14 of the frame and the flange 28 of the plate 25, are grasped by the operator and moved toward each other, 100 for decreasing the size of the frame, sufficient for insertion, and upon releasing the flange 28, the springs 29 extend the sections 10 and 11 for engaging the ends 14 and 15 with the sides of the window sash and retaining the invention in the window. This manner of mounting the screen 20 renders the edges thereof insect-tight so that flies and mosquitoes cannot pass through the frame when in use.

110

The embodiment of the invention herein illustrated and described is believed to be preferable, but it will be understood that the sections 10 and 11 may have their sides 5 of different form, so long as they are freely telescopingly movable, other minor changes being also permissible, without departing from the spirit and scope of my invention.

What I claim as new and desire to secure 10 by Letters Patent is:—

1. A window screen comprising U-shaped frame sections, telescopingly connected together, a roller journaled in one of said sections at one end of the frame, a slide plate 15 in said section adjacent the roller, a screen anchored in the other section, at the opposite end of the frame, and passing over said roller with its other end secured to said plate, and expansion springs tensioned between 20 the said sections adapted for normally maintaining the frame extended.

2. A window screen comprising U-shaped frame sections, telescopingly connected together, a roller journaled in one of said sections at one end of the frame, a slide plate 25 in said section adjacent the roller, a screen anchored in the other section, at the opposite end of the frame, and passing over said roller with its other end secured to said plate, the sides of said sections having axially alining bores, expansion springs in said 30 bores, connected to the opposite ends of the sections, and a guide rod for each of said springs carried by one of said sections.

3. A window screen comprising U-shaped sections having their sides telescopingly connected together, one within the other, the inclosing sides having slots and the inclosed

sides having grooves corresponding with 40 said slots, a roller journaled in the end of the inclosing side, a screen anchored at one end to the cross end of the section having the inclosed sides, the said screen extending through said grooves and slots, and passing over said roller, the sides of said sections 45 having corresponding grooves therein, a slide plate attached to the screen adjacent said roller, with ends slidably mounted in the grooves of the roller carrying section, and expansion springs tensioned between 50 said sections adapted to automatically extend the frame, upon the relative separating movement of the sections thereof.

4. A device of the class described comprising a rectangular frame formed of extensible sections, automatic means adapted for extending said sections, a roller journaled within the end of one section, a plate 55 slidably carried by said last named section, movable toward and from said roller, and a screen having one end secured to said plate and passing over said roller with the other end of the screen anchored to the section at the opposite end of the frame.

5. A window screen comprising sections 60 telescopingly connected together composed of metal-covered wood, a roller journaled in one section, a screen having one end anchored in the other section and passing over 65 said roller, adjusting means for the frame, secured to the free end of the screen, and projecting means resiliently positioned between 70 said sections adapted to automatically extend the frame when in use.

In testimony whereof I affix my signature. 75
JOSEPH A. S. SIMONE.
